UNITED STATES PATENT OFFICE.

BENJAMIN C. HAUKENBERRY, OF KANSAS CITY, MISSOURI.

SWITCH-STAND.

1,094,650.

Specification of Letters Patent. Patented Apr. 28, 1914.

Application filed November 4, 1912. Serial No. 729,203.

To all whom it may concern:

Be it known that I, BENJAMIN C. HAUKENBERRY, a citizen of the United States, residing at Kansas City, in the county of Jackson and State of Missouri, have invented certain new and useful Improvements in Switch-Stands, of which the following is a specification.

This invention relates to switch-stands, and my object is to produce a switch-stand which is adapted for manual operation from a point at the opposite side of the stand from the switch, whereby the operator is enabled to see trains approaching from both sides, and is so remote from the trackway that he is in no possible danger of being struck by a passing train.

Another object is to produce a switch-stand of such construction that it will readily free itself of any accumulation of ice or snow which will prevent its ready response to a pull on the operating lever.

Another object is to produce a switch-stand having means for automatically locking the switch in open or closed position.

Another object is to produce a switch-stand in which the operation of the switch is attended by a quarter rotation of the lamp casing; but not of the lamp, and hence without danger of extinguishment of the lights.

With these general objects in view, and others as hereinafter appear, the invention consists in certain novel and peculiar features of construction and organization as hereinafter described and claimed; and in order that it may be fully understood reference is to be had to the accompanying drawings, in which—

Figure 1, is a side view of a switch-stand embodying my invention. Fig. 2, is a rear view of the switch-stand. Fig. 3, is a top plan view of the switch-stand. Fig. 4, is an enlarged vertical section on line IV—IV of Fig. 1. Fig. 5, is a section on line V V of Fig. 4. Fig. 6, is a detail perspective view of a part of the hand lever whereby the switch is operated. Fig. 7, is a horizontal section on the line VII of Fig. 1 and showing the method of connecting the signal standard with the main standard of the switch-stand. Fig. 8, is an enlarged section on line VIII of Fig. 3. Fig. 9, is a section on line IX—IX of Fig. 8.

In the said drawings, 1 is a standard, and carried thereby there is a horizontal pivot pin 2, which extends substantially parallel

with the trackway not shown, and fulcrumed on said pin is a lever 3, provided above its pivotal point with a forwardly projecting arm 4, a rearwardly projecting arm 5, and a longitudinal slot 6.

7 is a lever fulcrumed on a pin 8 and equipped at its lower end with a pivot pin 9 which extends through the slot 6 and pivotally connects levers 3 and 7 together. Lever 7 is provided with a hinged extension 10, which can be swung from its operative position as indicated by dotted lines Fig. 1, to the inoperative position shown by full lines, for a purpose which hereinafter appears, and to secure the extension in rigid relation to the lever 7, when the former occupies its operative position, it is provided with a pivoted loop 11, adapted as the extension is swung upwardly to its operative position, to swing over an upwardly projecting lug 12 of lever 7, and thus lock the extension in its operative position, it being noted that this lug 12, also serves to relieve the loop of undue strain, when the extension, in operative position, is utilized to operate lever 3, in a manner hereinafter referred to.

To lock the lever 3, in either the full or dotted line position, shown by Fig. 1, a pin 13 extends slidably through the standard, and to effect the withdrawal or readvancement of said locking pin it is connected pivotally by a link 14 with a lever 15 fulcrumed at 16 on the standard, said lever being adapted for pivotal operation in a vertical plane at right angles to that in which lever 3 operates.

Lever 15 is provided with an offset lug or heel 17, through which it is pivotally connected by a link 18 with a pull lever 19 fulcrumed for movement in a vertical plane, on a bearing lug 20, rigid with standard 1, and at its front end said lever is provided with a weight 21 which is raised when the lever 19 is operated by foot power to effect the withdrawal of the locking pin 13 from the path of lever 3, and which returns by gravity to its original position when the foot pressure is removed, to effect the readvancement of said locking pin, it being noted that when the attendant operates the foot lever, the lever 15 swings in the direction indicated by the arrow Fig. 2, and that such movement of said lever is reversed when the attendant relaxes such foot pressure to permit the weight 21 to return the locking pin to operative position.

The lever 15 is provided with an extension or handle 22 so that it may be operated by hand, if desired, and also to make it more convenient for applying a mechanism for locking the locking pin in its advanced or operative position. As shown the standard is provided near its upper end with a suitable lock indicated only by the key-hole 23 and a bolt 24 projecting from the handle 22. 5 of the lever 15. As the use of locks in switch stands is common, applicant has merely indicated parts of said lock as it is not deemed necessary to fully illustrate the same because the special type of lock is immaterial. To exclude water and snow from the keyhole an ordinary keyhole guard 25 is pivoted to the standard 1 and is adapted to normally cover the keyhole in an obvious manner. 10

To insure the entrance of the bolt into the lock when the lever 15 swings to operative position, it is desirable to provide guiding means as a precaution against play of the lever, due to wear at its pivotal point, and 15 the guiding means shown consists of a pair of pins 26 and 27 projecting from the standard and flaring at their outer ends to facilitate the entrance of the lever between them. The outer end of one of the pins preferably 20 is in the form of an eye, as shown most clearly in Fig. 3, so that when the lever is in operative position, an eye 28 rigid therewith, will register with the eye of the said pin and thus permit the lever to be locked in 25 operative position by means of a padlock, not shown, in the event that the automatic locking mechanism identified by characters 23 and 24, is out of commission.

This switch stand is equipped with the 30 usual day and night signals 29 and 30, the former being the usual colored disk, and the latter a lamp. In the ordinary signals the lamp turns whenever the switch stand is operated, and it frequently happens that the 35 operation of the stand results in the extinguishment of the light. To guard against this result I provide the following construction: 31 is a shelf projecting diagonally from the standard toward the trackway, and 40 32 is a standard provided with a foot fitting upon and bolted as at 33 to said shelf, and in this connection it is desired to state that the shelf and standard 32 are of separable construction for convenience of the 45 removal of the switch stand, as otherwise part 32 is for all intents and purposes rigid with the standard 1. Standard 32 terminates at its upper end in a vertical cylindrical stub shaft 34, upon which is journaled a disk 35, 50 provided at diametrically opposite sides with a pair of short projecting arms 36. It is also provided at diametrically opposite sides and at right angles to the plane of the arms 36, with a pair of outwardly projecting arms 37 and 38, the latter carrying an

upright staff 39, for the direct support of the day signal 29. Above the disk 35 the stub shaft 34 terminates in a reduced angular portion 40, upon which nonrotatably fits a disk 41, forming the support of an ordinary 55 switch stand lamp 42, and inclosing said lamp is the customary four-lens casing 43 forming in conjunction with the lamp, the night signal 30, hereinbefore referred to, and in order that the lamp casing 43 shall 60 be turned each time the switch is thrown, said casing fits at its lower end around the disk 35 and is interlocked therewith. The preferred method of interlocking the casing is to provide its lower end with notches 44 65 adapted to receive the projecting arms 36, 37 and 38 of the said disk 35 as shown most clearly in Figure 5, this construction being desirable in order that the lamp proper may be readily accessible when it is necessary to 70 provide it with a new charge of oil or to trim or replace the wick.

I do not claim herein the particular construction of the signal above described.

To impart a quarter revolution to the 75 lamp casing and the day signal, with each operation of the switch, a link 45 is pivotally connected at its ends to a pin 46 carried by arm 37 of disk 35, and to a pin 47 pivoted to the upper end of lever 7. 95

48 is a bar pivotally connecting the lower end of lever 3 with the switch, not shown. This bar for the purpose of guarding against injury to the switch points, is preferably constructed as follows: 49 is a tubular member directly pivoted to the lower end of lever 3. 50 is a member directly connected at one end in the usual or any preferred manner to the switch and fitting telescopically at its opposite end in member 49 105 and provided with a longitudinal slot 51. 52 is a flanged sleeve fitting slidingly on member 50 and connected by tie bolts 53 to the flange 54 of member 49. 55 is a collar fitting slidingly on member 50. 56 is a 110 sleeve fitting at one end on sleeve 52 and at its opposite end secured by a pin 57 to collar 55, which pin extends through the slot 51 of member 50. 58 is an expansion coiled spring fitting around member 50 within 115 sleeve 56 and bearing at its opposite ends against sleeve 52 and collar 55 and normally holding the latter against the outer end of member 49, and 59 is a pin rigid with member 50 and normally bearing against the outer end of sleeve 52. Under ordinary conditions, that is when not being oscillated, the extension 10 of lever 7, occupies the position shown in full lines Fig. 1, 120 to avoid hiding or partially hiding the lens of the lamp, facing toward a train approaching the switch-stand from the side thereof occupied by said lever.

To operate the stand, the switchman, first 125 swings the extension 10 of said lever 7 to 130

the position shown by dotted lines *a*, and in so doing the loop 11 locks the extension rigidly in line with the lever as hereinbefore explained, so that the switchman by 5 grasping the extension can easily throw the switch, it being of course necessary to first unlock the switch by effecting the withdrawal of the locking bolt 13. In the operation explained, the casing of the night signal and the day signal, are turned a quarter revolution in the direction indicated by the adjacent arrows on Figs. 3 and 5 and the bar 48 moved in the direction of the arrow in Fig. 8, it being obvious that the pull on 10 member 49 of said bar 48, is imposed on member 50 through the instrumentality of sleeve 52, spring 58, collar 55 and pin 57, the spring being sufficiently strong to accomplish this operation without perceptible contraction. When the operation of the switch stand is reversed, the signals are restored to their original positions and the switch is likewise restored to its original position, and in the restoration of the switch the push on 15 member 49 is transmitted to member 50, through the collar 55, spring 58, sleeve 52 and pin 59. It will thus be seen that when the switch is operated from the stand, the spring 58 is inoperative, the function of said 20 spring being to yield to prevent injury to the switch points in the event lateral pressure is applied thereon by a passing train when the switch stand is locked, as in this case the switch point under ordinary conditions would be injured if provision was not made to permit member 50 to yield without corresponding movement on the part of the locked member 49. Assuming that the 25 switch points do move under such circumstances and therefore move member 50 in the direction indicated by the arrow hereinbefore referred to, the movement of said member 50 is transmitted through pin 59, sleeve 52 and the spring 58 yields to such movement of the sleeve. Should the switch be 30 moved in the reverse direction, it imparts movement through the pin 57 to collar 55 and sleeve 56, the spring yielding to accommodate this movement because the tie rods 35 53 prevents corresponding movement on the part of sleeve 52. It will thus be seen that provision is made to guard against injury to the switch points in the event movement is imparted to the same in either direction 40 when the switch stand is locked. The pin 2 on which lever 3 is fulcrumed, while sufficiently strong to resist the strain incident to the opening and closing of the switch, is preferably adapted under the imposition 45 of extraordinary strain, such for instance as might occur when the switch stand is locked and the switch is moved by a passing train in opposition to the locking pin, to break, as the breaking of such pin is preferable to injury to any other part of the 50

switch stand, because such pin can be easily and cheaply replaced.

From the above description it will be apparent that I have produced a switch stand embodying the features of advantage enumerated as desirable and which obviously is susceptible of modification in minor particulars without departing from the spirit and scope of the invention as defined by the appended claims. 75

I claim:

1. A switch stand, comprising a standard, a switch-operating lever, a locking pin therefor, means to unlock the lever by disengaging the pin therefrom, and automatic means 80 to restore the pin to its original position to lock the lever in the position to which it may be thrown after being unlocked.

2. A switch-stand, comprising a standard, a switch-operating lever, a locking pin therefor, means to unlock the lever by disengaging the pin therefrom, and a lever connected to said locking pin whereby the latter may be withdrawn from engagement with the first-named lever and when unresisted return 85 said locking pin to its original position to lock the first-named lever in the position to which it may be thrown after being unlocked. 90

3. A switch-stand comprising a standard, 95 a lever fulcrumed thereon, a lever pivoted to the first-named lever and fulcrumed on the stand, a locking pin fitting slidably in the standard and engaging the first-named lever to prevent movement thereof in one 100 direction, a third lever suitably fulcrumed and connected to the locking pin and adapted by force of gravity to hold said pin advanced to prevent movement of the first-named lever. 105

4. A switch-stand comprising a standard, a switch-operating lever, a locking pin therefor, means to unlock the lever by disengaging the pin therefrom, means to restore the pin to its original position to lock the lever 110 in the position to which it may be thrown after being unlocked, and a key-operated locking mechanism to lock the pin in its locking position.

5. A switch-stand comprising a standard, 115 a switch-operating lever, a locking pin therefor, means to unlock the lever by disengaging the pin therefrom, automatic means to restore the pin to its original position to lock the lever in the position to which it 120 may be thrown after being unlocked, and a key-operated locking mechanism to lock the pin in its locking position.

6. A switch-stand, comprising a standard, 125 a switch-operating lever, a locking pin therefor, means to unlock the lever by disengaging the pin therefrom, a lever connected to said locking pin whereby the latter may be withdrawn from engagement with the first-named lever and when unresisted return 130

4

said locking pin to its original position to lock the first-named lever in the position to which it may be thrown after being unlocked, and a key controlled locking mechanism to lock the pin in its locking position.

7. A switch-stand comprising a standard, a lever fulcrumed thereon, a lever pivoted to the first-named lever and fulcrumed on the stand, a locking pin fitting slidably in the standard and engaging the first-named lever to prevent movement thereof in one direction, a third lever suitably fulcrumed and connected to the locking pin and adapted by force of gravity to hold said pin advanced to prevent movement of the first-named lever, and a key-controlled locking mechanism to lock the pin in its locking position.

8. A switch stand comprising a standard, a rock lever fulcrumed on said standard, a lever fulcrumed on the standard and having a pin and slot connection with one end of said rock lever; a rod pivoted at one end to the lower end of said rock lever, a lever fulcrumed on the standard for operation in a plane at right angles to that in which the first-named levers operate, a locking pin linked to said last-named lever and extending slidably through the standard to prevent movement in one direction or the other of said rock lever, a weighted lever suitably

fulcrumed and linked to the lever linked to the locking pin and adapted to hold the locking pin yieldingly advanced, and key-controlled means for securing the locking pin in its advanced or locked position.

9. A switch stand, comprising a standard, a switch operating lever, and a locking device movable into locking position against one edge of the lever for one position thereof, and against the opposite edge of said lever in another position thereof.

10. A switch stand, comprising a standard, a switch operating lever, and a single sliding locking device for different positions of the lever, said device being movable automatically into locking engagement with the lever in the different positions of the latter.

11. A switch stand, comprising a standard, switch-operating lever, and a sliding locking device movable automatically into locking engagement with one edge of the lever in one position thereof, and with the opposite edge of said lever in another position thereof.

In testimony whereof I affix my signature, in the presence of two witnesses.
